GROUND FITTING

Carl G. Bondeson, Terryville, Conn., assignor to
 The Andrew Terry Company, Terryville, Conn.,
 a corporation of Connecticut

Application December 31, 1934, Serial No. 759,900

8 Claims. (Cl. 247—1)

This invention relates to grounding devices for electrical systems, and more particularly, to means for connecting an electrical conductor and its conduit, if such be provided, to a grounding pipe or the like.

An object of this invention is to provide a grounding device in which the several parts are rigid and in which a bare grounding wire may be securely clamped to one of the fixtures making up the device independently of the end of the grounding wire which is fastened to the fixture around a binding post or the like.

A further object of this invention is to provide means which may clamp the grounding wire independently of the end thereof in such a way that it may be employed to clamp and securely hold a metallic or non-metallic enclosure for the wire, or even a flexible armored conduit through which the grounding wire extends. In the latter case, not only is the wire grounded through the device of the present invention, but the flexible armored conduit will also be grounded because the clamp is in mechanical and electrical contact with the grounding pipe when the device of the present invention is applied thereto.

Other features and advantages will herein-after appear.

In the accompanying drawing, which illustrates one form of my invention, that at present preferred—

Figure 1 is a front view, showing the device of the present invention applied to a grounding pipe and holding in position a flexible armored cable through which the grounding wire extends.

Fig. 2 is a side view of the device shown in Fig. 1.

Fig. 3 is a front view, showing a bare grounding wire clamped to the device, the cover plate being removed and the bolt being shown in section, to illustrate the manner in which the end of the grounding wire lies in the channel provided for its reception.

Fig. 4 is an end view of the device shown in Figs. 1 and 2, but showing a grounding wire with a non-metallic covering clamped to the device.

Fig. 5 is a transverse sectional view of the parts shown in Fig. 3, but showing the coiled end of the grounding wire clamped in place by the cover plate and attaching bolt.

Fig. 6 is an exploded perspective view of the device of the present invention.

Fig. 7 is a view like the lower part of Fig. 4, but showing a rigid conduit secured by the clamp.

As shown in the accompanying drawing, the device of the present invention comprises two

fixtures, a fixture 10 which is to be attached to a grounding pipe 11 and a fixture 12 which, as shown in Figs. 1 and 2, may be attached to a flexible armored conduit 13 for a grounding wire, a covered grounding wire 14, as shown in Fig. 4, 5 or a bare grounding wire 15 as shown in Figs. 3 and 5, or a rigid conduit or pipe 45 as shown in Fig. 7.

The fixture 10 which engages the grounding pipe is made in two parts 10a and 10b. The part 10a is the main part and is provided with a V-shaped jaw 16 and a pair of laterally extending ears 17. The part 10b is a clamping plate and has a V-shaped jaw 18 and ears 19 matching with the ears 17 on the part 10a. According to the present invention, the ears 10b have screw-threaded apertures carrying draft screws 20 and the ears 17 on the part 10a are provided with apertures 21 to receive the screws 20.

So that the screw need not be completely removed from the clamping piece 10b to secure the parts 10a and 10b together, the apertures 21 in the ears 17 are provided with laterally opening entrance slots 22 wide enough to permit the screws 20 to enter the apertures 21. To hold the screws from shifting laterally out of the apertures 21, the ears are provided with depressed seats 23 for washers 24 carried by the screws 20. When the two parts 10a and 10b of the fixture 10 are placed on opposite sides of the grounding pipe 11 and the screws 20 are passed through the slots 22 and inserted in the apertures 21, the screws are tightened to draw the parts 10a and 10b together, and, in doing this, the washers 24 enter the seats 23 and hold the screws 20 and the parts 10a and 10b from shifting 30 relative to each other.

The jaws 16 and 18 may be provided with any suitable form of teeth to bite into and grip a grounding pipe, and they are so shaped and the draft screws 20 are made so long that the parts 10a and 10b may be clamped around pipes of 40 widely different diameters.

According to the present invention, the fixture 12 may be generally circular in shape. It has an end portion 25 which bears against a flat portion 26 on the part 10a of the fixture 10. The body of the fixture 12 has a central aperture 27 to align with an aperture 28 in the part 10a. The aperture 28 is preferably screw-threaded and receives a bolt 29 for securing the fixtures 10 and 12 together.

The fixture 12 is rotatable on the fixture 10 about the axis of the bolt 29, and for the purpose of aligning the fixtures 10 and 12 and guiding them in their rotating movements prior to the 55

insertion of the bolt 29, the fixture 10 may have a cylindrical boss 30 fitting a cylindrical socket 31 in the fixture 12, as shown in Fig. 5.

The fixture 12 is provided with an annular recess 32 to partially receive a coiled end 33 of the grounding wire 15, see Fig. 3. This coiled end 33 is confined in the recess 32 and secured in good mechanical and electrical contact with the fixture 12 by a cover plate 34 which, in the form 10 shown, is disk-shaped and is slipped on the bolt 29 so that when the latter is inserted through the fixtures 12 and 10, the plate 34 will cover the coiled end 33 of the grounding wire and clamp it in position. A lock washer 35 may be inserted 15 between the cover plate 34 and the head of the bolt to lock the bolt against turning under the influence of vibrations, etc.

If the plate 34 and bolt 29 were solely relied upon to secure the end 33 of the grounding wire 20 15 to the fixture 12, due to the absence of any jaw-like gripping action between the plate and the end of the grounding wire, a violent pull on the grounding wire might withdraw the end 33 from the channel 32.

25 To avoid this, the present invention provides means independent of the screw 29 for clamping the grounding wire to the fixture 12. For this purpose, the fixture 12 is provided with a lateral extension 36 having a channel 37 extending preferably radially from the fixture 12 and intersecting the recess 32.

In the form of the invention herein disclosed, the grounding wire 15 is clamped in the channel 37 by a clamping piece 38 which is preferably in the form of a strap having apertured ears 39 at each side and a channeled portion 40 between the apertured ears. When the channeled portion 40 is registered with the channeled portion 37 of the lateral extension 36, the apertures in the ears 39 register with threaded apertures 41 in ears 42 on the lateral extension to receive draft screws 43 carried by the ears 39.

When the clamping piece 40 is thus mounted on the lateral extension 36 and the screws 43 are backed out to permit sufficient clearance between the jaws constituted by the surfaces of the channels 37 and 40, the end of the grounding wire may be passed through these channels and coiled about the axis of the bolt 29 to lie in the recess 32. 50 Then the screws 43 are tightened to draw the clamping plate 38 toward the lateral extension 36 clamping the grounding wire with a jaw-like action. To further increase the jaw-like grip applied to the grounding wire by the channeled portions 37 and 40, each of these may be provided with ribs 44, see Figs. 5 and 6, to bite into the grounding wire.

When the grounding wire is thus held, it will be seen that strains are taken from the portion 60 thereof which is held under the cover plate 34, and thus while the channeled portions 38 and 40 or their ribs 44 may not make good or sufficient electrical contact between the grounding wire and the fixture 12, they do make good mechanical engagement and contact to relieve the strains 65 on the coiled end of the wire and prevent it from being drawn out of the fixture.

According to the present invention, the channels 37 and 40 in the lateral extension 36 and 70 clamping plate 38 respectively are substantially V-shaped so as to firmly grip the wire and so as to serve to grip things of various diameters, and the screws 43 are made long enough to permit a wide separation of the clamping plate 40 from 75 the lateral extension 36. Accordingly, instead of

inserting the bared end of the grounding wire 15 between the lateral extension and the clamping plate, the non-metallic covering of a covered grounding wire may be clamped to the fixture as shown in Fig. 4. Or, if desired, the end of the flexible armored conduit 13 may be inserted between the lateral extension 36 and the clamping plate 38 to rigidly and securely hold the armored conduit to the fixture, as shown in Figs. 1 and 2.

Again, as shown in Fig. 7, the rigid conduit or pipe 45 may be inserted in the channels 37 and 40 to be clamped to the fixture 12 by the clamping piece 38 and screws 43.

With the device of the present invention, it is not necessary to place a bend in the grounding wire or its conduit in order that it may be inserted through the channels 37 and 40, for the fixture 12 is rotatable on the fixture 10, and hence the axis of the channels may be brought into alignment with the grounding wire or its conduit regardless of the angle at which the same approaches the grounding pipe.

Variations and modifications may be made within the scope of this invention, and portions of the improvements may be used without others.

Having thus described the invention, what is claimed as new and for which it is desired to obtain Letters Patent, is:—

1. An electrical connection comprising a fixture having screw-operated clamping jaws with pipe-engaging yoke portions, for attachment to a grounding pipe; a second fixture; and means connecting the second fixture to the pipe-engaging yoke portion of one of said jaws for relative rotary movements, said second fixture having a lug 30 extending laterally of the connecting means, provided with a channel to receive a bare wire, a covered wire, or a flexible armored conduit, and a pair of ears at each side of said channel, and a clamping piece adapted to overlie said lateral extension of said second fixture and provided with ears corresponding to the ears on said lateral extension, and screws extending through said ears on the clamping piece and on the lateral extension for drawing the clamping piece toward the lateral extension to clamp a bare or covered grounding wire, or flexible armored conduit for the grounding wire to the second fixture.

2. An electrical connection comprising a fixture having screw-operated clamping jaws for attachment to a ground pipe; a second fixture; and means for connecting the fixtures together for relative rotary movements, said second fixture having a lateral extension provided with a channel to receive a bare wire, a covered wire, or a flexible armored conduit and a pair of ears at each side of the channel, and a clamping piece adapted to overlie said lateral extension of said second fixture and provided with ears corresponding to the ears on said lateral extension, and screws extending through said ears on the clamping piece and on the lateral extension for drawing the clamping piece toward the lateral extension to clamp a bare or covered grounding wire, or flexible armored conduit for the grounding wire to the second fixture, and said second fixture also having an annular recess intersected by the channel thereof, within which recess the end of a grounding wire passing between the lateral extension and said clamping piece may be confined 70 by the means for connecting the fixtures together.

3. An electrical connection comprising a fixture having screw-operated clamping jaws for attachment to a grounding pipe; a second fix- 75

ture; and means for connecting the fixtures together for relative rotary movements, said second fixture having a lateral extension provided with a channel to receive a bare wire, a covered wire, or a flexible armored conduit and a pair of ears at each side of the channel, and a clamping piece adapted to overlie said lateral extension of said second fixture and provided with ears corresponding to the ears on said lateral extension, and screws extending through said ears on the clamping piece and on the lateral extension for drawing the clamping piece toward the lateral extension to clamp a bare or covered grounding wire, or flexible armored conduit for the grounding 10 wire to the second fixture, and said second fixture having a circular recess intersected by the channel thereof, within which recess a coiled end of the grounding wire passing between the lateral extension and the clamping piece may be confined, said means for securing the fixtures together comprising a screw passing through aligned apertures in said fixtures, said screw when tightened to secure the fixtures in adjusted relation pressing a plate lying over said circular 20 recess against the coiled end of the wire contained therein.

4. An electrical connection comprising a fixture having screw-operated clamping jaws with pipe-engaging yoke portions, for attachment to a 30 grounding pipe; a second fixture; means connecting the second fixture to the pipe-engaging yoke portion of one of said jaws for relative rotary movements, including a screw for fastening the end of a grounding wire to said second fixture 35 in electrical contact therewith; and auxiliary means including a strap having a pair of clamping ears for clamping the grounding wire to said second fixture to relieve from pulling strains the end of the grounding wire attached by said screw.

40 5. An electrical connection comprising a fixture having screw-operated clamping jaws with pipe-engaging yoke portions, for attachment to a grounding pipe; a second fixture; means connecting the second fixture to the pipe-engaging yoke portion of one of said jaws for relative rotary movements, including a screw for fastening the end of a grounding wire to said second fixture 45 in electrical contact therewith; and a mov-

able jaw clamp having a strap with a pair of clamping ears for securing the grounding wire to said second fixture to relieve from pulling strains the end of the grounding wire attached by said screw.

5 6. An electrical connection comprising a fixture having screw-operated clamping jaws with pipe-engaging yoke portions, for attachment to a grounding pipe; a second fixture; means connecting the second fixture to the pipe-engaging yoke portion of one of said jaws for relative rotary movements, including a screw for fastening the end of a grounding wire to said second fixture in electrical contact therewith; and a rigid two-jaw clamp having a strap with a pair of clamping 10 ears for securing the grounding wire to said second fixture to relieve from pulling strains the end of the grounding wire attached by said screw.

15 7. An electrical connection comprising a fixture having screw-operated clamping jaws with pipe-engaging yoke portions, for attachment to a grounding pipe; a second fixture; means connecting the second fixture to the pipe-engaging yoke portion of one of said jaws for relative rotary movements, including a screw for fastening the end of a grounding wire to said second fixture in electrical contact therewith; and an adjustable 20 clamp on said second fixture including a strap having a pair of clamping ears for engaging and securing a grounding wire or a flexible armored 25 conduit to said second fixture.

30 8. An electrical connection comprising a fixture having screw-operated clamping jaws with pipe-engaging yoke portions, for attachment to a grounding pipe; a second fixture; means connecting the second fixture to the pipe-engaging yoke portion of one of said jaws for relative rotary movements, including a screw for fastening the end of a grounding wire to said second fixture 35 in electrical contact therewith; and auxiliary means including a strap having a pair of clamping ears for clamping the grounding wire to said second fixture to relieve from pulling strains the end of the grounding wire attached by said screw, 40 said clamping means being adjustable to engage 45 and hold either a bare or covered grounding wire.

CARL G. BONDESON.
